His attorney.

UNITED STATES PATENT OFFICE.

MICHAEL ANDREW DROITCOUR, OF DELPHOS, OHIO.

TWO-SHEET STOP-FEED DETECTOR MEANS.

1,218,988.

Specification of Letters Patent. Patented Mar. 13, 1917.

Application filed May 4, 1916. Serial No. 95,384.

To all whom it may concern:

Be it known that I, MICHAEL ANDREW DROITCOUR, a citizen of the United States, and a resident of Delphos, in the county of Van Wert and State of Ohio, have invented a certain new and useful Two-Sheet Stop-Feed Detector Means; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to an automatic multiple-sheet stop-feed means for use in connection with any mechanism to which sheets of paper are intermittently fed, as, for instance, a printing press, folding machine, etc.

In separating paper for feeding to any mechanism for operating thereon it sometimes occurs that two sheets or more will be advanced in place of one, and it is the object of my invention to provide an improved means of simple and efficient construction for detecting such multiple feeding of sheets and effecting an automatic stopping of the associated mechanism.

The invention is fully described in the following specification, and while in its broader aspect it is capable of embodiment in numerous forms a preferred embodiment thereof is illustrated in the accompanying drawings, in which,—

Figure 1 is a perspective view of a portion of a sheet feeding mechanism equipped with my detector means with the parts of the latter in normal position. Fig. 2 is a side elevation thereof with the sheet-coacting part of the detector means moved from normal position. Fig. 3 is a section on the line $x-x$ in Fig. 2 and Fig. 4 is a plan of the spaced electric terminals or contacts of the detector means.

Referring to the drawings, 1 designates one of the tape wheel shafts of a sheet feeding mechanism, said shaft having sets of tape wheels 2 and 3 thereon around which respective sheet-advancing tapes 4 and 5 extend. In advance and above the plane of the shaft 1 is located a stationary bar 6, which is mounted in any suitable manner transversely of the direction of feed of the sheets by the tapes 4 and 5.

Projecting from the rod 6 toward the shaft 1, but in a plane over the same, are two arms 7 and 8 disposed side by side with the arm 7 fixedly carried by the rod and the arm 8 loosely carried thereby. The arm 7 has a part 9 projecting transversely therefrom beneath the arm 8 adjacent to its outer end and forming an anvil on which the arm 8 is adapted to loosely rest.

The arm 8 carries a block 10 on its top side, and mounted on this block are two electrical contacts 11, 11, disposed in spaced relation and each having a lead wire 12 attached thereto. The lead wires 12 are in circuit with any suitable electrically operated stop means for the mechanism, with which the detector means is associated. As numerous types of such electrically operated stop means have been used and are well known in the art it is not thought necessary to illustrate the same herein. Mounted over the contacts 11, 11 for movements into and out of circuit closing contact therewith is a pole-piece or switch part 13, which is carried, in the present instance, by the finger 14, which projects transversely from the upper end of a vertically-disposed lever 15 that is fulcrumed to the free end of the arm 8, as at 16. The pole-piece 13, in the present instance, is loosely mounted on the lower end of a bolt 17 which is pendants carried by the free end portion of the finger 14, and a coiled compression spring 18 is disposed between the pole-piece and finger to yieldingly retain them in spaced relation.

The lower arm of the lever 15, which is the detector member of the device, is disposed over one of the tape wheels 2 and terminates at its lower end in a segmental foot piece 19, the arc of which is preferably concentric to the swinging axis of the lever. A coiled contractile spring 20, in the present instance, connects a pin or projection 21 on the fixed arm 7 with a pin or projection 22 on the upper arm of the lever 15 and serves to yieldingly retain the lever 15 in substantially upright position with the pole piece 13 in circuit closing contact with the contacts 11. A pin 23 on the outer end of the arm 7 coacts with the lower arm of the lever 15 to limit the spring-influenced movements thereof.

In adjusting my detector means for use after the parts thereof have been assembled as above described, the arm 7 is adjusted on the rod 6 so that the anvil 9 will have

contact with the arm 8 and support the foot-piece or detector part 19 of the lever 15 very slightly above the subjacent sheet feeding tape 4 at a point over the respective wheel 5 2, the free space therebetween being, say .001 of an inch, or less, than the full thickness of a sheet of the smallest gage or weight customarily run on the mechanism. This adjustment having been made, it is practically permanent for the running of different 10 jobs having the sheets thereof of different thickness, it being only necessary for the operator before running a job to tear a piece from one of the sheets *a* thereof and place it between the anvil 9 and arm 8, said piece 15 being designated 24 thus raising the detector part 19 a distance above the tape 4 equal to the thickness of the sheet plus the fractional thickness of the sheet for which the 20 parts are permanently set. It is now apparent that when the feeding mechanism is in operation a single sheet of a thickness for which the detector means has been adjusted will pass freely under the shoe 19 without 25 contact therewith, or at least sufficient contact therewith, to effect a swinging thereof, and that should two or more sheets be fed at a time the combined thickness thereof will be greater than the space between the 30 tape 4 and the detector part 19, so that the upper sheet will frictionally coat with the lower segmental surface of the part 19 and cause a swinging of the lower end of the lever in the direction of feed of the sheets 35 and against the tension of the spring 20, as illustrated in Fig. 2. The swinging of the lever 15 in this manner causes a raising of the pole-piece or switch member 13 from bridging contact with the contacts 11, thus 40 breaking the electrical circuit in which said contacts are disposed and effecting a stopping of the running of the mechanism by reason of the breaking of the electric circuit controlling the running thereof, as is 45 well understood in the art.

I am aware that it has been common to provide a screw-gage, or micrometer adjustment in connection with a detector means of the class described to permit the detector 50 means to be adjusted to the thickness of the paper that is being run. In all cases, however, of which I am aware, it is necessary for the operator to manipulate the screw-gage or micrometer adjustment to suit the 55 thickness of the sheets being run, thereby requiring for each job a very delicate adjustment on the part of the operator, which adjustment is difficult to make unless the operator has had considerable experience in 60 such connection. For instance, if sheets .005 of an inch in thickness were to be run, the detector means would be set so that the free space between the tape and the detector member of the mechanism would be .005 of 65 an inch plus a fraction of the thickness of

the sheet, thus allowing one sheet to freely pass between the detector member and feed tape without operating the former, but preventing two or more sheets from passing therebetween without causing a movement 70 of the detector member and a subsequent throwing off or stopping of the mechanism.

It will be apparent that with my improved detector means no delicate adjustment of the same is necessary on the part of the operator after it has been initially set, as it is only necessary for him to insert a small piece 24 of the paper to be run between the anvil 9 and arm 8 to thus effect an accurate adjustment of the parts in a quick 80 and simple manner to suit the thickness of the sheets to be run.

I wish it understood that my invention is not limited to any specific construction, arrangement or form of the parts as it is 85 capable of numerous modifications without departing from the spirit of the claims.

Having thus described my invention, what I claim as new and desire to secure by Letters Patent, is—

1. The combination with means over which sheets are fed, of a vertically movable member, a detector part movably carried by said member, an element for limiting the lowering movements of said member and co-operating therewith to support the detector part in such relation to said means as to provide a predetermined minimum spacing between said means and part, said spacing being increased a predetermined extent by 90 inserting a piece of a sheet to be run between the coacting stop parts of said member and element whereby the feeding of two or more sheets in superimposed order over said means will cause a movement of said detector part 95 relative to said member, and means actuated to break an electric circuit when said detector part is moved by the passage of sheets thereunder.

2. In combination a stationary part having an anvil, a vertically movable member adapted to rest on and having its lowering movements limited by said anvil, an electric switch, a detector part swingingly carried by said member and having connection with the movable member of the switch, sheet-advancing means disposed in predetermined spaced subjacent relation to said detector part whereby a switch opening movement will be imparted to the detector part by the 110 passage of a sheet between it and said means and be prevented, unless more than one sheet 115 is fed, by the insertion of a piece of a sheet 120 to be fed between said anvil and member.

3. In a detector mechanism of the class 125 described, in combination, a stationary part, a vertically movable member having its lowering movements limited by said part, a detector part movably carried by said member, an electric circuit-breaking element car- 130

ried by said detector part and sheet-advancing means disposed below the detector part whereby the advancing movement of a sheet between said means and detector part in coaction with the latter will move said latter to impart a circuit breaking movement to said element, the spacing of said means and detector part being varied by inserting spacing members of different thickness between said stationary part and member.

4. In a detector mechanism of the class described, in combination, an adjustable stationary part, a vertically movable member having its lowering movements limited by said part, a detector part movably carried by said member, an electric circuit-breaking element carried by said detector part and sheet-advancing means disposed below the detector part whereby the advancing movement of a sheet between said means and detector part in coaction with the latter will move said latter to impart a circuit breaking movement to said element, the spacing of said means and detector part being varied by inserting spacing members of different thickness between said stationary part and member.

5. In a detector mechanism of the class described, a sheet-advancing means, a movable member supported above said means at a distance less than the thickness of a sheet, an electric switch having connection with and operated by said member, a movable support for said member, a limiting stop for coating with said support to determine the spacing of said advancing means and movable member, and a spacing part of a thickness substantially equal to the thickness of the sheets to be run inserted between said support and stop, whereby said member is moved when more than one sheet is fed at a time between said member and advancing means.

6. In a detector mechanism of the class described, a sheet-advancing means, a member movably supported above said means and movable by the passage of a plurality of sheets together over said means, said member and means having an initial spacing less than the thickness of a sheet, an electric switch operable by the movement of said member, a movable support movably carrying said member, a limiting stop for said support to determine the initial spacing of said member and means, and a spacing means of predetermined thickness removably inserted between said support and stop.

7. In a detector mechanism of the class described, a sheet-advancing means, a member swingingly supported above said means and having a predetermined initial spacing with respect thereto, an electric switch operable by swinging movements of said member, a vertically movable support carrying said member, a stop coöperating with said

support to determine the initial spacing of said member and means, and a spacing part of predetermined thickness removably inserted between said support and stop to increase the spacing of said member and means a sufficient extent to permit one but not two sheets to pass therebetween without swingingly moving said member.

8. In a detector mechanism of the class described, a sheet-advancing means, a member supported for substantially horizontal movements above said means and movable by the advancing of sheets over said means, an electric switch operated by sheet-actuated movements of said member, a vertically movable support for said member, a stop coacting with said support to normally support said member in predetermined relation to said means and a spacing part of predetermined thickness removably inserted between said support and stop whereby said member and means are spaced to permit one but not two sheets of predetermined thickness to pass therebetween without moving said member.

9. In a detector mechanism of the class described, a sheet-advancing means, a member swingingly supported above said means and having swinging movements imparted thereto by the advancing of a plurality of sheets over said means, an electric switch operated by sheet-actuated movements of said member, a vertically movable support for said member, an adjustable stop for said support, and a spacing part of predetermined thickness removably inserted between said support and stop and coöperating therewith to provide a spacing between said member and means which is equal to the thickness of the sheets to be run plus a fractional part thereof, whereby one but not two sheets will pass between the member and support without moving the former.

10. In a detector mechanism of the class described, a sheet-advancing means, a member swingingly supported above said means and normally maintaining one position with respect thereto, said member and means having a predetermined initial spacing, an electric switch having connection with and being opened by abnormal movements of said member, a vertically movable support for said member, a stop coöperating with said support to determine the initial spacing of said member and means, a spacing part of a thickness equal to the thickness of a sheet to be run removably inserted between said support and stop to coöperate therewith to increase the spacing between said member and means a predetermined extent.

11. In a detector mechanism of the class described, a sheet-advancing means, a member swingingly supported above said means, a movable support for said member, a stop coöperating with said support to support said member in predetermined relation to

4

said means, an electric switch carried by said support and operated to break circuit by a sheet-actuated movement of said member, means yieldingly retaining said member in 5 one position of its movement with respect to said support, a spacing part of a thickness substantially equal to the thickness of a sheet to be run inserted between said stop and support to increase the spacing between said 10 member and means a predetermined extent whereby one but not two sheets of a thickness for which the mechanism is set will pass between said means and member without moving the latter.

15 12. In a detector mechanism of the class described, a sheet-advancing means, a member swingingly supported above said means, an electric switch having a part carried by said member and movable to open the switch

circuit by sheet-actuated movements of said 20 member, a vertically movable arm carrying said switch and member, an adjustable stop for supporting said arm and coacting therewith to maintain said member in predetermined spaced relation to said means, and a 25 spacing part consisting of a piece of a sheet to be run inserted between said stop and arm to increase the spacing between said member and means a corresponding extent, whereby one but not two sheets of a thickness for which the mechanism is set will be 30 permitted to pass between said member and means without imparting switch opening movements to said member.

In testimony whereof, I have hereunto 35 signed my name to this specification.

MICHAEL ANDREW DROITCOUR.
